US00D945393S

(12) **United States Design Patent** (10) **Patent No.:** **US D945,393 S**
Mead et al. (45) **Date of Patent:** **** Mar. 8, 2022**

(54) **MODULAR RADIO ENCLOSURE**

(71) Applicant: **ConcealFab Corporation**, Colorado Springs, CO (US)

(72) Inventors: **Jeffrey Mead**, Colorado Springs, CO (US); **Jonathan Morris**, Colorado Springs, CO (US)

(73) Assignee: **ConcealFab Corporation**, Colorado Springs, CO (US)

(**) Term: **15 Years**

(21) Appl. No.: **29/759,088**

(22) Filed: **Nov. 19, 2020**

(51) LOC (13) Cl. **14-03**

(52) U.S. Cl.

USPC **D14/188; D14/217; D14/230; D14/265**

(57) **CLAIM**

The ornamental design for a modular radio enclosure, as shown and described.

DESCRIPTION

FIG. 1 is a perspective view of a modular radio enclosure, showing the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view of thereof; and,

FIG. 7 is a bottom view thereof.

The broken lines in the drawings depict portions of the modular radio enclosure that form no part of the claimed design.

1 Claim, 7 Drawing Sheets
